ELECTROMAGNETIC DEVICE

Herman G. Blosser, Pittsburgh, and Robert M. Laurenson, Rosedale Heights, Pa., assignors to The Union Switch & Signal Company, Swissvale, Pa., a corporation of Pennsylvania

Application May 26, 1942, Serial No. 444,512

7 Claims. (Cl. 200—93)

Our invention relates to electromagnetic devices, and particularly to devices provided with contacts operated by a vibrating element for periodically interrupting or pole changing the supply of direct current to the primary of a transformer to produce alternating current in the secondary thereof.

One object of our invention is to provide a device of the type described which may be driven from a pilot source of alternating current, and which will accurately follow the frequency of the pilot source irrespective of changes in the mass or resilient characteristics of the vibrating element caused by wear in the contacts and irrespective of changes in the magnitude of the energizing current.

Another object of our invention is to provide a highly efficient device of the type described which will operate on a relatively small amount of alternating current such as can be obtained from a source of direct current through the medium of a small inexpensive tuned reed vibrator or alternator.

A further object of our invention is to provide a device of the type described that requires a small amount of power for its energization and is capable of operating a relatively large number of pole changing contacts each capable of carrying relatively large currents.

A still further object of our invention is to provide a device of the type described which when energized will start without appreciable delay, and which has an exceptionally long life.

According to our invention, the device comprises a contact carrying vibrating reed armature rigidly anchored at one end to a fixed support, and cooperating at its free end with two pairs of longitudinally spaced poles which together with the armature comprise part of a motor element for causing the armature to vibrate. The poles of each pair are connected with the corresponding poles of the other pair by backstraps, and are each provided with bifurcated pole faces the bifurcations of each of which are laterally spaced apart a distance which is sufficient to permit the armature to swing into the space formed between them. The bifurcations of the two pole pieces nearest the free end of the armature are disposed in spaced confronting relation so that air gaps are formed between them, but the bifurcations of the other pair are disposed with their confronting ends touching so that they form a low reluctance magnetic path to and from the armature, and also around the armature, without interfering with its move-

ment. The two backstraps are bridged by a permanent magnet which polarizes the two pole pieces nearest the free end of the armature. Shunting of the flux from this magnet through the other pair of pole pieces is prevented by non-magnetic bushings interposed between these pole pieces and the associated backstraps. The energizing winding of the device surrounds the armature between the two pairs of pole pieces, and due to the polarizing effect of the permanent magnet the reed armature swings at its free end toward one pole piece or the other depending upon the polarity of the current supplied to this winding. The reed armature and associated contacts are so designed that the resulting assembly has a natural period of vibration which is slightly higher than the frequency at which it is desired to have the armature vibrate, whereby when the energizing winding is supplied with current of the frequency at which it is desired to have the armature vibrate the armature will vibrate at this frequency irrespective of changes in its mass and resilient characteristics caused by contact wear.

Other objects and characteristic features of our invention will become apparent as the description proceeds.

We shall describe one form of device embodying our invention, and shall then point out the novel features thereof in claims.

In the accompanying drawings, Fig. 1 is a vertical sectional view showing one form of device embodying our invention. Fig. 2 is a right-hand side view of the device shown in Fig. 1. Fig. 3 is a detail sectional view of a portion of the relay taken at right angles to Fig. 1. Figs. 4 and 5 are detail sectional views taken on the lines IV—IV and V—V, respectively, of Fig. 1.

Similar reference characters refer to similar parts in each of the several views.

Referring to the drawings, the device in the form here illustrated comprises a suitable case consisting of a top plate 1 of insulating material secured to the upper end of a substantially U-shaped non-magnetic bracket 2, a metallic base plate 3 secured to the lower end of the bracket 2, and a transparent glass cylinder 4 clamped between the top plate 1 and the base plate 3. A gasket 5 of cork or other suitable material is interposed between the top plate 1 and the upper end of the cylinder 4, and a similar gasket 6 is interposed between the bottom plate and the lower end of the cylinder, thereby sealing the case against the entry of dust or other foreign substances.

A vertically disposed vibrating reed armature

7 (see Fig. 3) of suitable magnetizable material is suspended from a bracket 8 secured to the underside of the top plate, and this armature cooperates at its lower end with upper and lower pairs of pole pieces 9, 10, and 11, 12, respectively, which pole pieces together with the armature comprise part of a motor element for causing the armature to vibrate. The armature is relatively stiff, and in order to cause it to vibrate in the desired manner it is essential that the upper end of the armature be rigidly fixed against movement. To this end, the armature is fastened as by riveting to the bracket 8, and is also securely clamped against one side of a depending portion 8a of the bracket 8 by means of a clamping block 13 and clamping bolts 14. Moreover, the bracket 8 is disposed in a groove 15 formed in the underside of the top plate, and is securely fastened to the top plate by means of two machine screws 16 and two terminal posts 17. The terminal posts 17 are in the form of studs, the lower ends of which are screwed into tapped holes provided in the bracket, and the upper ends of which project above the top plate and carry the usual clamping nuts 18 for securing circuit wires to the terminal posts. It will be apparent that the terminal posts are electrically connected through the medium of the bracket with the armature 7, and these terminal posts provide a convenient means for establishing external electrical contact with the armature for a purpose which will appear presently.

The motor element includes in addition to the pole pieces two vertically disposed bars 20 and 21 which are secured, respectively, to the legs 2a and 2b of the bracket 2 by means of machine screws 51 which pass through clearance holes in the bars and are screwed into tapped holes formed in inwardly projecting lugs 2c and 2d provided on the legs 2a and 2b. These bars, which are of magnetizable material, are provided at their upper ends with split portions 20a and 21a terminating in aligned circular openings 20b and 21b, and at their lower ends with other split portions 20c and 21c terminating in aligned circular openings 20d and 21d. The upper openings 20b and 21b receive with a snug fit split non-magnetic bushings 22 and 23, which bushings, in turn, receive the rounded outer ends of the pole pieces 9 and 10, while the lower openings 20d and 21d receive with a snug fit the rounded outer ends of the lower pole pieces 11 and 12. Each split portion is provided with an associated clamping screw 24 which, when tightened, draws the two halves of the split portion together and thereby clamps the pole pieces securely in a fixed position with respect to the associated bar. It will be obvious that the bar 20 serves as a backstrap to magnetically connect the two pole pieces 9 and 11 together, and that the bar 21 similarly serves as a backstrap to magnetically connect the two pole pieces 10 and 12 together, but that, due to the non-magnetic bushings 22 and 23, a relatively high reluctance path is provided between the pole pieces 9 and 10 and the associated bars.

The pole pieces 9, 10, 11 and 12 are each provided at their inner ends with bifurcated pole faces, and the bifurcations on each pole piece are laterally spaced apart a distance which is slightly greater than the width of the armature so that the armature when vibrated is free to swing into the space between them. As best seen in Fig. 5, the lower pole pieces 11 and 12 are so adjusted that the ends of the bifurcations are in confront-

ing relation but are spaced apart by air gaps of sufficient lengths so that the armature will not swing between the bifurcations on either pole piece until it has moved away from its mid stroke position an appreciable distance. The other pole pieces 9 and 10 are so adjusted that the ends of their bifurcations are also in confronting relation but these ends, instead of being spaced apart, are in actual contact as shown in Fig. 4 so that they form a low reluctance magnetic path around the armature from one pole piece to the other without interfering with its movement, and also from the armature to either pole piece in any position of the armature.

The motor element further includes a pair of permanent magnets 25 and 26, and an energizing winding 27. The permanent magnets bridge the bars 20 and 21 directly opposite the lower pair of pole pieces 11 and 12, and serve to polarize these pole pieces. Shunting of the flux from these magnets through the other pair of pole pieces is prevented for the most part by the non-magnetic gaps provided between the pole pieces 9 and 10 and bars 20 and 21 by the bushings 22 and 23 described hereinbefore. The magnets are secured in place by brackets 29 and 30 and bolts 31.

The energizing winding 27 is wound on a hollow spool 32 which surrounds the armature with considerable clearance between the two pairs of pole pieces. This spool rests on the pole pieces of the lower pair, and is maintained in the desired lateral position by means of notches 32a in the upper spool head, which notches receive the bars 20 and 21. Vertical movement of the spool 32 is prevented by spring clips 33 interposed between the upper spool head and the upper pole pieces 9 and 10. The winding 27 is provided with leads 27a secured to terminal posts 341 mounted on the top plate 1.

The armature 7 carries a contact assembly comprising a plurality of flexible contact fingers 34 and 35, each of which cooperates with a fixed contact member 34a or 35a to close a contact 34-34a or 35-35a according as the armature is swung in one direction or the other from the position shown. The contact fingers are disposed in pairs and are secured at their upper ends by means of studs 36 to conducting brackets 37. The brackets 37 extend transversely to the armature, and are secured intermediate their ends to the armature at a point well below the point of maximum stress in order to minimize the chance of breakage of the armature. Interposed between the brackets and the fingers are conducting strips 38 which receive the fingers and serve to maintain the fingers in the desired vertical positions, and disposed on the studs between the brackets are spacing blocks 39 which add to the rigidity of the contact assembly. The positions of the flexible fingers when the fingers are out of engagement with the associated fixed contact members are determined by stops 40 which are clamped against the outer faces of the fingers by means of the associated studs 36, and each of which stops is provided at its lower end with an opening through which a low resistance contact button carried by the associated finger projects. The stops are so adjusted by bending them that the fingers will break the contacts in the desired positions when the armature is oscillating. It will be apparent that the fingers 34 and 35 are each electrically connected through the medium of the blocks 38, studs 36 and brackets 37.

with the armature 7, and since, as was pointed out hereinbefore, the armature 7 is electrically connected with the terminal posts 17, it follows that the terminal posts 17 provide a convenient means for obtaining external electrical contact with the contact fingers 34 and 35.

The fixed contact members 34a and 35a are similar to the fixed contact members 18a and 18b described and claimed in an application for Letters Patent of the United States, Serial No. 304,811, filed by Herman G. Blosser on November 16, 1939; for Electrical relays, which application became Patent No. 2,285,890 on June 9, 1942; and are adjustably secured to the lower ends of terminal posts 45 mounted on the top plate 1 in a manner which is also described in the said Blosser application. It is believed to be unnecessary, therefore, to describe the construction and arrangement of these fixed contact members any further herein.

In operation, the winding 27 is supplied with alternating current of the frequency at which it is desired to have the armature 7 vibrate, and due to the polarizing effect of the permanent magnets the lower end of the armature moves toward the pole piece 11 or the pole piece 12 depending upon the instantaneous polarity of the alternating current in the winding 27 at any one time. In other words, the armature is poled in one direction for the positive half of the alternating current cycle and in the opposite direction for the negative half of the alternating current cycle; and since the pole pieces 11 and 12 are always poled in the same direction due to the permanent magnet flux, an alternating force is produced in the lower end of the armature which causes the armature to oscillate. As is well understood, the power required to cause the armature to oscillate will be a minimum when the armature and associated contact assembly are mechanically tuned to oscillate at the same frequency as the frequency of the alternating current which is supplied to winding 27. We have found, however, that if the vibrating parts are tuned to resonance at the exact frequency at which it is desired to have the armature oscillate, the change in mass and resilient characteristics of the vibrating parts caused by contact wear will cause the amplitude of vibration of the armature to change, and as a result, if sufficient wear takes place the armature will stall. This is undesirable, and in accordance with our invention we avoid this change in amplitude by so proportioning the vibrating parts that they have a resonant frequency which is slightly higher, for example 8 per cent higher, than the frequency of the energizing current. This insures that the armature will always be in the mid position when the maximum force is applied to the armature in either direction by the fluxes traversing the armature, and tends to provide constancy of armature amplitude under varying conditions of contact wear.

It should be particularly pointed out that since the lower pole pieces are bifurcated in the manner described, the driving force applied to the armature in either direction is cut off as soon as the armature moves between the bifurcations. This construction materially assists in maintaining the armature amplitude constant irrespective of changes in the magnitude of the applied alternating current.

It should also be particularly pointed out that since the upper pole pieces are bifurcated and are disposed with the confronting ends of the

bifurcations in actual contact, these pole pieces serve to by-pass the permanent magnet flux around the armature and to provide a return path for the electromagnet flux induced in the armature without introducing any force on the armature itself. That is to say, if these pole pieces were separated in a manner similar to the lower pole pieces, a torque would be applied to the armature at the upper pole pieces which would be in opposition to that applied at the lower pole pieces, and the efficiency of the device would thereby be materially lessened.

Devices embodying our invention are particularly suitable for, although in no way limited to, use for supplying alternating current from a source of direct current in certain forms of railway signaling systems where no commercial source of alternating current of the desired frequency is available, or if a commercial source of alternating current of the desired frequency is available, then as a standby source to maintain the signaling system in operation in the event of an interruption in the commercial source. When used for either purpose, a pilot source of alternating current for operating the device may be readily obtained through the medium of a vibrator which, due to the small amount of power required to drive the device, can be inexpensive, and which will accurately maintain its frequency for a long period of time. Since the device operates at the frequency of the pilot source, the frequency of the current generated by the device is unaffected by contact wear, and the resulting combination has a very long life.

Although we have herein shown and described only one form of electromagnetic device embodying our invention, it is understood that various changes and modifications may be made therein within the scope of the appended claims without departing from the spirit and scope of our invention.

Having thus described our invention, what we claim is:

1. An electromagnetic device comprising a vibrating reed armature anchored at one end and cooperating at its free end with a pair of pole pieces having bifurcated pole faces disposed with their bifurcations in spaced confronting relation, the bifurcations on each said pole piece being far enough apart to permit said armature to swing into the space between them, other pole means surrounding said armature with clearance intermediate its ends and providing a low reluctance path from said armature to said pole means, magnetizable means providing a relatively high reluctance path from the pole pieces of said pair of pole pieces to said pole means, means for polarizing said pole pieces, and means for producing a flux in said armature which reacts with the polarized flux supplied to said pole pieces to cause said armature to oscillate.

2. An electromagnetic device comprising a vibrating reed armature anchored at one end and cooperating at its free end with a pair of pole pieces having bifurcated pole faces disposed with their bifurcations in spaced confronting relation, the bifurcations on each said pole piece being far enough apart to permit said armature to swing into the space between them, other pole means surrounding said armature with clearance intermediate its ends and providing a low reluctance path from said armature to said pole means, magnetizable means providing a relatively high reluctance path from the pole pieces of said pair of pole pieces to said pole means,

means for polarizing said pole pieces, and means for producing an alternating flux of a particular frequency in said armature, the parts being so proportioned that said armature is resonant at a frequency slightly higher than the frequency of said alternating flux.

3. An electromagnetic device comprising a vibrating reed armature anchored at one end and cooperating at its free end with a pair of pole pieces having bifurcated pole faces disposed with their bifurcations in spaced confronting relation, the bifurcations on each said pole piece being far enough apart to permit said armature to swing into the space between them, other pole means surrounding said armature with clearance intermediate its ends and providing a low reluctance path from said armature to said pole means, magnetizable means providing a relatively high reluctance path from the pole pieces of said pair of pole pieces to said pole means, means for polarizing said pole pieces, and a winding surrounding said armature between said pole pieces and said pole means, the parts being so proportioned that when said winding is supplied with alternating current of a particular frequency said armature will oscillate.

4. An electromagnetic device comprising a vibrating reed armature anchored at one end and cooperating at its free end with two spaced pairs of pole pieces, said pole pieces being formed with bifurcated pole faces the bifurcations of which are far enough apart to permit said armature to freely enter the space between them, the two pole pieces of the pair nearest the free end of said armature being disposed with their bifurcations in spaced confronting relation and the pole pieces of the other pair being disposed with their bifurcations touching to provide a low reluctance magnetic path from one pole piece to the other past said armature and from said armature to both said pole pieces, magnetizable members connecting the corresponding pole pieces of the two pairs of pole pieces together, means for polarizing the pole pieces nearest the free end of said armature, means for providing a relatively high reluctance path for said polarizing flux from said members to the pole pieces of the other pair, and means for producing a flux in said armature to cause said armature to oscillate.

5. An electromagnetic device comprising a vibrating reed armature rigidly anchored at one end and cooperating at its free end with two spaced pairs of pole pieces, said pole pieces being formed with bifurcated pole faces the bifurcations of which are far enough apart to permit said armature to freely enter the space between them, the two pole pieces of the pair nearest the free end of said armature being disposed with their bifurcations in spaced confronting relation and the pole pieces of the other pair being disposed with their bifurcations touching to provide a low reluctance magnetic path from one pole piece to the other past said armature and from said armature to both said pole pieces, magnetizable members connecting the corresponding pole pieces of the two pairs of pole pieces together, means for polarizing the pole pieces nearest the free end of said armature, means for providing a relatively high reluctance path for said polarizing flux from said members to the pole pieces of the other pair, means for producing a flux in said armature to cause said

armature to oscillate, a contact assembly secured to said armature and including a plurality of flexible contact fingers, and a fixed contact cooperating with each finger, said armature and contact assembly being so proportioned that they have a resonant frequency slightly higher than the frequency at which said armature is caused to oscillate to provide constancy of armature amplitude irrespective of contact wear.

6. An electromagnetic device comprising a vibrating reed armature rigidly anchored at one end and cooperating at its free end with two spaced pairs of pole pieces, said pole pieces being formed with bifurcated pole faces the bifurcations of which are far enough apart to permit said armature to freely enter the space between them, the two pole pieces of the pair nearest the free end of said armature being disposed with their bifurcations in spaced confronting relation and the pole pieces of the other pair being disposed with their bifurcations touching to provide a low reluctance magnetic path from one pole piece to the other past said armature and from said armature to both said pole pieces, magnetizable members connecting the corresponding pole pieces of the two pairs of pole pieces together, means for polarizing the pole pieces nearest the free end of said armature, means for providing a relatively high reluctance path for said polarizing flux from said members to the pole pieces of the other pair, and means for producing an alternating flux in said armature having a frequency slightly below its natural resonant frequency to cause said armature to oscillate at the frequency of said flux.

7. An electromagnetic device comprising a vibrating reed armature rigidly anchored at one end and cooperating at its free end with two spaced pairs of pole pieces, said pole pieces being formed with bifurcated pole faces the bifurcations of which are far enough apart to permit said armature to freely enter the space between them, the two pole pieces of the pair nearest the free end of said armature being disposed with their bifurcations in spaced confronting relation and the pole pieces of the other pair being disposed with their bifurcations touching to provide a low reluctance magnetic path from one pole piece to the other past said armature and from said armature to both said pole pieces, magnetizable members connecting the corresponding pole pieces of the two pairs of pole pieces together, means for polarizing the pole pieces nearest the free end of said armature, means for providing a relatively high reluctance path for said polarizing flux from said members to the pole pieces of the other pair, a winding surrounding said armature between said pairs of pole pieces for producing an alternating flux of a particular frequency in said armature, a contact assembly including a plurality of pairs of flexible contact fingers secured to said armature, and fixed contacts cooperating with said contact fingers, said armature and contact assembly being proportioned to have a resonant frequency of vibration slightly higher than the frequency of said flux, whereby the amplitude of vibration of said armature will remain substantially constant irrespective of contact wear or changes in resiliency of the vibrating parts caused thereby.

HERMAN G. BLOSSER.
ROBERT M. LAURENSEN.
